UNITED STATES PATENT OFFICE.

SAMUEL B. COOK, OF LAUREL, MISSISSIPPI, ASSIGNOR OF ONE-THIRD TO
EDWARD D. PEIRCE, OF LAUREL, MISSISSIPPI.

WASHBOARD.

No. 851,497.

Specification of Letters Patent.

Patented April 23, 1907.

Application filed October 14, 1905. Serial No. 282,748.

To all whom it may concern:

Be it known that I, SAMUEL B. COOK, a citizen of the United States, residing at Laurel, in the county of Jones and State of Mississippi, have invented a new and useful Improvement in Washboards, of which the following is a specification.

My invention is an improvement in the class of washboards whose scrubbing surface is formed of a series of rectangular bars arranged transversely and held detachably in the side bars of the frame.

The invention is illustrated in the accompanying drawing in which,

Figure 1 is a perspective view of my invention complete. Fig. 2 is a central longitudinal section thereof. Fig. 3 is a transverse section taken centrally through the board. Fig. 4 illustrates an arrangement of the transverse scrub bars slightly different from that shown in Fig. 2. Fig. 5 is a perspective view of one of the scrub bars. Fig. 6 shows the parts of the clamping device removed from the board but in operative relation to each other. Fig. 7 shows a slightly different form of scrubbing bars.

The frame of my washboard A is composed of the side bars 1 and 2 rigidly secured together at their upper ends by the top bars 3 and 4, and a board serving as the soap holder 5, interposed centrally between said top bars.

The side bars 1 and 2 are provided in their inner faces with deep grooves *a'* which extend from their lower ends up to the bar 4, and are of uniform diameter throughout their length.

The scrubbing portion of my board is formed of a series of scrub bars B. These bars are preferably square in cross section as shown in Figs. 2 and 4 and extend transversely across the washboard. At their ends they are provided with tenons *b'* whose sides are inclined to the side of the main portions of the bars. These reduced portions are of a size to be snugly received into the recesses *a'* of the side bars, and when thus received with their sides inclined as just described the corners of the said main sections of the bars will be presented to each other as illustrated in Fig. 2, the grooves *a* in the side bars being of uniform diameter throughout, and extending to the lower ends of the side bars, the tenons *b'* of the scrubbing bars, B, may be readily inserted and slid up in the grooves to form

the complete scrubbing board or surface. 55 These square bars are held securely in engagement with each other by the upper and lower scrub or holding bars 7 and 8, which preferably are formed as shown. These bars are provided on their ends with tenons similar to the tenons *b'* of the square bars B, and also adapted to be received into the grooves *a'* of the side bars of the board.

Each of the bars 7 and 8 is provided with a corner normally so disposed as to engage and 65 bear against the adjacent corner of the upper and lower scrub bars B respectively, to hold all the said bars in engagement with each other. The bar 7 is provided on its top with a flat face which fits firmly against the bar 4. 70 The lower bar 8 is flat on its under side and to the latter is secured a rightangular plate *c'* which forms part of a clamping device C; see especially Fig. 6.

A portion of the clamping device indicated 75 by Figs. *c²*, *c³* is practically a clip, the same being pivoted by screw *c⁴*, to the outer sides of the bars 2 and the bent portion passing over the bars and in front of the portion *c⁶* of the angular plates *c'*. The side bar 2 is preferably hinged at 9, and thus the clamping devices 6 serve not only for holding the scrubbing bars, including the top and bottom bars 7 and 8, in due position, but also to lock all the parts together, to wit: the side bars 1 80 and 2 and the bars constituting the scrubbing surface. By raising the clip, comprising the parts indicated by *c²*, *c³*, the same will be disengaged from the angular plates *c'* so that all the bars may be slid downwardly and 85 removed from the side bars 1 and 2.

It will be seen that when the exposed corners of the scrub bars B have become worn, the bars may be taken out, turned one fourth of a revolution and replaced in position. 95 This will provide the board with two new scrubbing surfaces. Hence it is seen that one of my washboards is equivalent to four of the ordinary kind. Moreover when all four of the corners of the scrub bars B are worn off, a 100 new set of bars can be supplied at a trifling cost which will again render the board practically new.

By hinging the side bar 2 in the manner shown, it may be opened to allow any one or 105 all of the scrubbing bars to be readily removed or turned as may be required.

From Fig. 3 it will be seen that the grooves

a' are considerably deeper than the length of the tenons *b'* of the scrub bars. The open portion of these grooves forms a passageway downward through the sides of the board to the bottom of the tub, for the grit and sediment that is forced from very dirty material, for it will be seen that when the clothes saturated with water are forced over the top face of the board, the water will naturally be forced out of the cloth into the angular grooves formed between the scrub bars, and this water together with the grit and dirt which it dislodges from the clothes will find an easy way of escape along said grooves to their ends which open into the grooves *a'* of the side bars through which latter the grit is conveyed to the bottom of the tub and is not intermixed with the other clothing in the wash.

Fig. 4 shows a slightly different way of arranging the scrub bars with reference to each other in the washboard. In that figure it will be noticed that their corners do not meet as in Fig. 2, but that the sides near the corners slightly lap each other. This effect is produced by making the grooves *a'* somewhat larger than the tenons *b'* of the scrub bars, and serves a very good purpose when the bars have been well worn on two sides, and it is desirable to turn them a fourth of a revolution as specified above, to form a new washing surface for the board, in which case the edges if brought directly together as illustrated in

Fig. 2, would be worn so irregularly and always more at the center of the bar than at their ends, so that they would not fit together and the water and sediment dislodged by rubbing would run through between the bars instead of being conveyed along them to the grooves *a'*. This lapping of the bar B may be easily provided for to any degree by simply making the bars in the form of an oblong rectangular in cross section as illustrated in Fig. 7.

Having thus described my invention, what I claim as new and desire to secure by Letters Patent is:

In a washboard of the class indicated, the combination, with side bars having internal longitudinal grooves extending to their lower ends, of a part intervening such side bars and constituting the scrubbing surface of the board, such part having tenons adapted to fit and slide in the grooves of the side bars, clamping devices comprising rightangular plates attached to the lower edge of the scrubbing part, and clips pivoted to the side bars and adapted, when in normal position, to overlap the lower portions of said plates and thus lock the scrubbing part in place, as shown and described.

SAMUEL B. COOK.
